WIG DRESSING STAND

John T. Mergens and Paulita D. Mergens, San Diego,
Calif. (both of 9250 Kenwood Drive, Spring Valley, Calif. 92114)

Filed July 23, 1971, Ser. No. 165,871

Term of patent 14 years

Int. Cl. D28—03

U.S. Cl. D86—10 A

FIG. 1 is a perspective view of a wig dressing stand, showing my new design;

FIG. 2 is a side elevational view thereof, as taken from the right hand side of FIG. 1;

FIG. 3 is a top plan view thereof; and

FIG. 4 is a bottom plan view thereof.

We claim:

The ornamental design for a wig dressing stand, as shown.
